UNITED STATES PATENT OFFICE.

WILLIAM HACKLY CHURCH, OF SUPERB, SASKATCHEWAN, CANADA.

GRAIN-STOOKER.

1,240,823.

Specification of Letters Patent. Patented Sept. 25, 1917.

Application filed June 2, 1916. Serial No. 101,424.

To all whom it may concern:

Be it known that I, WILLIAM HACKLY CHURCH, a subject of the King of Great Britain, and resident of Superb, in the Province of Saskatchewan, Dominion of Canada, have invented certain new and useful Improvements in Grain-Stookers, of which the following is the specification.

This invention relates to improvements in grain stookers and the objects of the invention are to facilitate in forming the sheaves of grain into a stook and readily discharge the same, to permit of the heads of the sheaves being readily bunched together during the operation of dumping the stooks, to readily pack the sheaves in position, and other objects to be made clear hereafter, and it consists essentially of the improved construction particularly described and set forth 20 in the following specification and accompanying drawings forming part of the same.

In the drawings,

Figure 1 is an end elevation of the improved machine.

Fig. 2 is a plan view of the same.

Fig. 3 is a side view of the machine showing the location of the packing arms and the means for operating the same.

Fig. 4 is an enlarged perspective view, 30 partly in section, of the packing arms and showing the means for preventing the sheaves being delivered to the basket collector when the stook is being dumped.

Fig. 5 is a side elevation of the machine.

Fig. 6 is a longitudinal section of the 35 spring controlled drum controlling the action of the upper portion of the basket collector.

Fig. 7 is a fragmentary elevation, part 40 being in section, of the cam member and its coacting roller controlling the closing of the upper portion of the basket collector.

Fig. 8 is a perspective view of a chain 45 tightener adapted to coact with the main drive of the machine.

Fig. 9 is a fragmentary perspective view of the mechanism controlling the rotary motion of the basket collector.

Like characters of reference refer to like 50 parts in the several figures.

Referring to the drawings, A represents the improved stooker which is operatively connected to the binder B adjacent to the binder deck D in a manner to be made clear 55 hereafter. The stooker A consists of the frame E rotatably supporting the inner end

of the shaft 11 which is provided intermediate of its ends with a curvilinear portion 12 adapted to carry the lower portion 13 of the basket collector F.

60

The outer end of the shaft 11 carries a ground wheel 14 rotatably mounted thereon and is further provided with a crank member 15 rigidly connected thereto and carrying an angular lever 16 pivotally mounted 65 thereon, the inner end of which is substantially curvilinear as shown at 17 and adapted to engage with the pin 18 thereby limiting the outward motion of the said lever which is adapted to be pressed inwardly to 70 engage with the spokes of the wheel 14 in a manner to be made clear hereafter.

Rotary motion is transmitted to the shaft 11 by the disk 10 provided with the curvilinear slot 19 having a plurality of notches 75 20 therein adapted to engage with the offset end of the lever 21, the other end of which is engaged with one of the orifices 22 provided in the crank arm 23 of the spindle 24, the opposite end of which is provided with 80 a crank arm 25 angularly disposed to the crank arm 23 and carrying a cam member 26 adjustably mounted thereon.

The lever 16 is provided with a projection 27 designed to be engaged by the spring 28 85 adapted to hold the said lever normally disengaged from the spokes of the wheel 14, the said lever being adapted to be moved into engagement with the said spokes through the medium of the bell crank 29 90 pivotally mounted on the frame E and operatively connected by the link 30 with the bell crank 31 mounted on the said frame.

The opposite end of the bell crank 31 is connected by a flexible member 32 which 95 passes around suitable guide pulleys 33 and extends to a point adjacent to the driver's seat. The link 30 passes through a guide bracket 34 and is provided with a spring 35 located between the bell crank 29 and the 100 said bracket.

During the forward motion of the wheel 14 rotary motion is transmitted to the shaft 11, which through the medium of the chain 36 operatively connecting the sprockets 37 105 and 37^a rotates the shaft 38 which carries a beveled pinion 39 meshing with the beveled pinion 40 mounted on the transversely extending shaft 41 so transmitting rotating motion thereto.

This shaft 41 is rotatably mounted in the bearings 42 carried by the frame E and is 110

provided intermediate of its length with sprockets 43 operatively connected by the chains 44 to the sprockets 45 carried by the shaft 46 rotatably mounted in one of the 5 arms of the inverted Y-shaped end brackets 48 of the frame G, the said shaft being provided intermediate of its length with crank members 49 on which the packing arms 50 are pivotally mounted.

10 The forward ends of the packing arms 50 are substantially V-shaped while the rear end is pivotally connected to the lower end of the links 51, the upper ends of which are pivotally connected to a U-shaped bracket 52 carried by the frame E.

15 The upper ends of the inverted Y-shaped brackets 48 are pivotally mounted on the shaft 41 and are operatively connected by an inverted U-shaped rod 53 forming part of 20 the frame G, while the third arm of the said brackets is connected by a transversely extending rod 54 carrying a spring 54^a adapted to hold the frame G in a normal retracted position. The outer end of the crank shaft 25 46 makes engagement with the lower offset end 55 of the lever 56 which is pivotally mounted to the frame E and provided with an offset arm 57 adapted to engage with the angular stop member 58 rigidly mounted on 30 the lower portion 13 of the basket collector F.

35 The Y-shaped brackets 48 are also operatively connected by flexible members 59 with the bar 60 which is provided intermediate of its length with upwardly extending arms 61 slidably mounted in the inverted V-shaped frame 62, the inner face of which is adapted to guide the sheaves into the basket collector F, the flexible members 59 being designed to engage intermediate of 40 their length with the guide pulleys 63 suitably secured to the frame E.

45 The upper portion 64 of the basket collector F is hinged to the lower portion 13, the motion of the upper portion being controlled by the curvilinear arms 65 rigidly secured to the curvilinear portion 12 of the shaft 11. This upper portion 64 carries a pair of brackets 67 rigidly attached thereto and operatively supports the drum 66, the 50 rotation of which is controlled by the spiral spring 68 wound around the pin 69 having one end rigidly attached to one of the brackets 67 and the other end extending through the periphery of the said drum.

55 The drum is also provided with a pair of projections 70 to which the ends of the flexible members 71 are connected, the said flexible members engaging with guide pulleys 72 mounted on the upper end of the 60 curvilinear arms 65, the other end of the flexible members being connected to the lower end of the spiral spring 73 which is coiled around the curvilinear arm 65 so that the said flexible members are always in a 65 state of tension.

Located adjacent to the curvilinear arm 65 is a resilient packing member 74 formed in a substantially U-shaped portion which projects into the basket collector F, the free ends of the said member being rigidly connected to the upper portion 64 of the basket collector. The upper portion 64 of the basket collector is further provided with a bracket 75 carrying a roller 76 on the upper end thereof adapted to coact with the cam portion 26 which is provided with a curvilinear slot 77 with which the adjusting bolt 78 carried by the crank arm 25 is adapted to engage.

Coacting with the lever 16 is a frame 79 80 which is almost completely circular, being provided however with a gap portion which permits of the said lever being freed from engagement with the spokes, the said frame being adapted to engage with the lever 16 85 and hold the same in engagement with the spokes until the wheel 14 has rotated through one revolution when the offset end 80 of the frame allows the lever to be released and returned under the action of the spring 28 90 to its normally disengaged position.

During the period when the lever 16 is in engagement with the wheel 14, rotary motion is transmitted to the shaft 11, the inner end of which is provided with a cam 95 member 81 designed to engage with the roller 82 carried by the offset arm 83 mounted on the U-shaped rod 53 which rod is, due to the displacement of the offset lever 56, thrown inwardly permitting the engagement 100 of the roller 82 and cam 81 to take place.

Simultaneously with this rotation, it is desirable that the sheaves should not be fed to the basket collector F, and to this end a lever 84 is pivotally mounted on an angle 105 bracket 85 carried by the frame G, the inner end of the lever being bifurcated to embrace the U-shaped rod 53, the outer end being provided with a pinion 86 adapted to mesh with the pinion 87 carried by the shaft 110 41 and the pinion 88 carried by the conveyer roller 89 thereby resulting in the conveyer H being rendered inoperative.

This conveyer may be of any usual construction and is carried by the frame 90 115 pivotally mounted to the upper roller 89, while below the lower end of the said frame an adjustable frame I is mounted which consists of a flanged plate 91 operatively connected intermediate of its breadth to the 120 lower end of the links 92, the upper ends of which are pivotally connected to the brackets 93 carried by the frame E, the adjustment of this frame I being controlled by a lever 94 pivotally mounted intermediate of its 125 length to one of the brackets 93 and pivotally connected at its lower end to the said frame, the lever being provided with a detent 95 coacting with the quadrant 96 rigidly mounted on the bracket 93. 130

The adjustable frame I is pivotally connected to one end of the link C which is attached to the binder frame, and it will readily be seen that by utilizing a pivotal attachment of this nature the binder may be raised or lowered to suit the length of grain being cut, while the said frame may be adjusted to correspond with the elevation of the binder.

10 Simultaneously with the rotation of the basket collector F the door J which closes the end of the said basket is designed to be withdrawn from contact therewith under the action of gravity, and to this end the 15 door is attached to the frame 97 hung from the frame E.

The door is normally held in closed position by the roller 98 carried by the crank arm 99 of the spindle 100, the other end of 20 which is provided with a crank arm 101 having a plurality of orifices therethrough with which one end of the link 102 engages, the other end of the link being adjustably connected to the lever 21 which is operatively 25 connected to the spring 103 anchored to the frame E.

The assembly of the machine will be readily understood from the foregoing description.

30 When the machine is in use the sheaves are delivered from the binder deck D and delivered to the frame E where they are engaged by the conveyer H and delivered to the basket collector F, the upper portion 35 64 of which is normally held in an open position as will be seen by reference to Fig. 1.

In the forward motion of the machine it will be understood that the sprocket wheel 40 37 which is rigidly attached to the wheel 14 is rotated thereby and rotary motion is transmitted through the chain drive 36 to the shaft 38 which in turn rotates the shaft 41 causing the packing arms 50 to be reciprocated through the bottom portion 13 of the basket collector so that as the sheaves are delivered to the basket collector F they are tightly packed in position by means of the said arms. When the desired number 45 50 of sheaves have been delivered to the basket collector F the driver exerts a pull on the flexible member 32 thereby rotating the bell crank 31 and causing the bell crank 29 to throw the angle lever 16 into engagement 55 with the spokes of the wheel 14 so that during the rotation of the wheel 14 the shaft 11 will be rotated in a forward direction, dumping the sheaves in the basket collector on the ground in the form of a stool.

60 During the rotation of the shaft 11 it will be understood that the lever 21 through the medium of the link 102 actuates the spindle 100 and disengages the roller 98 from the door J permitting the same under 65 the action of gravity to become disengaged

from the lower end of the basket collector F and at the same time the lever 21 also actuates the spindle 24 causing the cam member 26 to engage with the roller 69 and so close the upper portion 64 on the lower 70 portion 13 of the basket collector.

During the period of dumping, the resilient U-shaped member 74 engages with the heads of the sheaves, bunching the same together while the stool is being deposited 75 on the ground so that the base of the stool will be extended and the heads will lie close together.

When the basket collector is being thus located the angle stop member 58 engages 80 with the upper offset arm 57 of the lever 56, the lower end of which moves or swings the frame G about the shaft 41, so that as the lower end of the frame moves outwardly, the rod 53 carried by the upper end of the 85 frame moves inwardly toward the inverted V-shaped frame 62. This movement of the rod 53, due to its engagement with the bifurcated end of the lever 84, moves or rotates the said lever which is fulcrumed intermediate of its length to the bracket 85 so that as the longer arm of the lever is moved toward the inverted V-shaped frame 62 the shorter arm is moved outwardly and disengages the pinion 86 from the pinions 90 87 and 88 so rendering the conveyer H inoperative.

Simultaneously with the throwing of the pinion 86 out of gear the bar 60 is operated, due to the motion of the frame G, and results in the elevating of the arms 61 which project above the frame 62 and prevent any sheaves from being inadvertently delivered to the basket collector F. During the rotation of the basket collector F the frame G 100 is held in this displaced position by the cam 81 which engages with the roller 82 carried by the arm 83 attached to the U-shaped bar 53 forming a portion of the said frame, and after the basket has completed one 110 single revolution the roller 82 becomes disengaged from the cam 81 permitting the frame G to return to its normal position in which the lever 84 is actuated and the pinion 86 thrown into gear with the pinions 115 87 and 88 resulting in the operation of the conveyer H which delivers the sheaves to the basket collector F.

The shaft 41 is rotated from the main drive of the machine as already described 120 and the packing arms 50 tightly pack the sheaves in position in the basket collector which, when a sufficient number of sheaves have been delivered thereto, is again dumped in the manner already described. 125

What I claim as my invention is:

1. In a stooking machine and in combination, a basket collector, means for delivering sheaves of grain to the basket collector, means for packing the grain in position, 130

and means for rotating the basket collector through a complete revolution in a forward direction.

2. In a stooking machine and in combination, a basket collector, means for delivering sheaves of grain to the basket collector, packing arms operating through the basket collector, means for reciprocating the packing arms, and means for rotating the basket collector through a complete revolution in a forward direction.

3. In a stooking machine and in combination, a basket collector, a conveyer coöperating therewith, packing arms operating through the basket collector, means for reciprocating the packing arms, means for rotating the basket collector in a forward direction through a complete revolution, and means for simultaneously rendering the conveyer and packing arms inoperative during the rotation of the basket.

4. In a stooking machine and in combination, a basket collector, an inverted V-shaped frame located adjacent to the basket collector, means for rotating the basket collector forwardly through a complete revolution, a plurality of arms slidably mounted in the V-shaped frame, and means for elevating the arms simultaneously with the rotation of the basket.

5. In a stooking machine and in combination, a basket collector, means for rotating the basket collector forwardly through a complete revolution, a pivotally mounted frame located adjacent to the basket collector, packing arms carried by the said frame, means for reciprocating the packing arms, a conveyer coöperating with the basket collector, and a lever provided with a bifurcated end embracing the said frame and operatively connecting the frame and conveyer, as and for the purpose specified.

6. In a stooking machine and in combination, a basket collector, means for rotating the basket collector forwardly through a complete revolution, a frame located adja-

cent to the basket collector, packing arms carried by the frame, means for reciprocating the packing arms, an offset lever operatively connected to the frame and provided with an offset arm, and a stop member on the basket collector coacting with the arm of the offset lever.

7. In a stooking machine and in combination, a basket collector formed in two portions hingedly connected together, a curvilinear arm located above one of the portions of the basket, a spring embracing the said arm, flexible members operatively connected to the spring, a rotatably mounted drum carried by the basket operatively connected to the other end of the flexible member, and resilient means coacting with the drum and automatically retaining the two portions of the basket in open position.

8. In a stooking machine and in combination, a shaft provided with a curvilinear portion intermediate of its length, a basket operatively connected to the curvilinear portion of the shaft and formed in an upper and lower portion, a wheel rotatably mounted in the shaft, a lever pivotally connected to the shaft and coacting with the wheel to rotate the basket through a complete revolution, and a curvilinear frame coacting with the said lever.

9. In a stooking machine and in combination, a basket collector, a traction wheel, an angle lever coacting with the traction wheel, resilient means for normally disengaging the angle lever with the traction wheel, means for actuating the angle lever, and a curvilinear frame coacting with the angle lever and holding the same in contact with the wheel during a complete revolution of the wheel.

In witness whereof I have hereunto set my hand in the presence of two witnesses.

WILLIAM HACKLY CHURCH.
